United States Patent Office

Des. 209,152
Patented Nov. 7, 1967

209,152

MUSICAL TOY

Frank Fusco, Monroe, Norman Charles Gold, New York, and William Gold, Great Neck, N.Y., assignors to Louis Marx & Co., Inc., New York, N.Y., a corporation of
New York

Filed Jan. 6, 1967, Ser. No. 5,326

Term of patent 7 years

(Cl. D34—15)

FIG. 1

FIG. 1 is a front and right side perspective view of a musical toy embodying our new design;

FIG. 2 is a left side elevational view thereof; and
FIG. 3 is a rear elevational view thereof.

We claim:

The ornamental design for a musical toy, as shown.
